FOOT REST

Filed July 5, 1921

UNITED STATES PATENT OFFICE.

JAMES G. HONTOS, OF CHICAGO, ILLINOIS, ASSIGNOR TO SAFETY SHOE REST & SHOE SHINING COMPANY, OF CHICAGO, ILLINOIS, A COPARTNERSHIP CONSISTING OF EMILIO SANTANIELLO, GEORGE W. DARDAVESIS, AND JAMES G. HONTOS.

FOOT REST.

Application filed July 5, 1921. Serial No. 482,533.

To all whom it may concern:

Be it known that I, JAMES G. HONTOS, a citizen of the United States, residing at Chicago, in the county of Cook and State of Illinois, have invented certain new and useful improvements in Foot Rests, of which the following is a specification.

This invention relates to a foot rest for a shoe shining stand whereon is a chair for the customer; in particular it is concerned with certain improvements by which a pair of shoe supports are mounted so as to be slidable forwardly or rearwardly of the seat as desired.

An embodiment of this invention in its preferred form is shown in the accompanying drawing wherein—

Figure 1 is a side elevation of a seat mounted upon a shoe shining stand, an adjustable foot rest being arranged on the side thereof;

Fig. 2 is a plan view of the foot rest in extended position;

Fig. 3 is a central longitudinal section through the foot rest, which is here shown in rearmost position;

Fig. 4 is a fragmentary detail in section taken on line 4—4 of Fig. 3; and

Fig. 5 is a rear elevation of the slide rods with connecting plate therebetween.

In the drawing is shown a chair A supported upon a pedestal B which may be mounted upon the usual platform C of a shoe shining stand. Mounted upon the platform is the adjustable foot rest D of my invention, one such device being preferably arranged on either side of the chair. Any suitable construction of chair, platform, etc., may be employed.

The present invention is concerned entirely with the foot rest which, in the form shown, makes use of a frame E that is preferably in the form of an inverted box having end walls 6 and 7 each of which is provided with an outwardly turned flange 8.

According to the construction shown, the under sides of these flanges are ribbed as at 9 at their outer extremities and are further formed with downwardly depending bosses 10 through each of which is an opening to receive a bolt 11 that passes through the platform C to lock the frame in place. It will be observed that the frame so formed is rigidly mounted upon the platform by means

of the bolts 11, and that the bosses 10 also enter slightly into the body of the platform so as to resist any lateral thrusts upon the frame.

Arranged within the end walls 6 and 7 of the frame E are three bores each forming a bearing for a slideable rod. Two of these bores are arranged preferably side by side so as to receive rods designated as F and G respectively, the third or intermediate bore being shown as slightly below the others so as to receive an extension rod H, all as appears best in Fig. 4. At their rear ends 15 the two slide rods F and G are preferably squared (see Fig. 5) to receive a connecting plate 16 which is formed also with two square openings, any suitable locking means, such as a cotter pin 17, being employed to hold the plate in place. Because of this construction the plate 16 affords a rigid connection between the two slide rods at their rear ends such as to resist any torsional movements of one with respect to the other. Means may also be provided for cushioning the contact of this end plate 16 with the proximate end wall of the frame whenever the slide rods are pulled forward to their limit, and for this purpose I have shown a short coiled spring 18, one on each of the slide rods, adjacent the plate, and, if desired, a facing 19 of fibre, felt, or other suitable material may be carried by the plate to assist in this action.

Connecting the forward ends of the two slide rods is a member 20 from which up-stands a pair of lugs 21 which support a plate 22 which constitutes the shoe support. This member is securely fastened to the two slide rods and is movable toward or from the frame E. To cushion the contact of the member with the frame, coiled springs 23 are arranged one on each rod F and G adjacent the forward frame end, as shown in Fig. 3.

It will be apparent that when the foot rest is extended forwardly, it will be held in horizontal position solely through the support afforded by the frame E. The strain on the two rods F and G may be reduced by the use of an extension rod H which is preferably of short length as compared with the others. Carried by the front end of the rod H is a supporting plate 25 that underlies each of the rods

F and G, and which, if desired, may be faced on its rear side as at 26 with a piece of fibre, felt, or other cushioning material. The rear end of the extension rod will be engaged by the connecting plate 16 whenever the foot rest is pulled forward for an appreciable distance. Continued movement of the foot rest will result in the extension rod also moving forward, 10 so that the supporting plate 25 is thereby advanced well out in front to yield additional support to the rods F and G. When the foot rest is made to recede, the position of the extension rod will also be similarly affected just as soon as the foot rest has moved sufficiently to engage with the supporting plate 25, as shown in Fig. 3.

It will be apparent that the foot rest herein shown embodies numerous features 20 which may be combined together as shown, or be used separately or in different combinations, if desired, and that the form and relationing of the various parts may be also modified within considerable limits 25 without departing from the spirit of my invention as defined by the claims following.

I claim:

1. In a device of the kind described, the

combination of a frame formed to provide a pair of bearings a rod slidably mounted 30 in each bearing, a member connecting the forward ends of the rods together, a shoe support carried by the member, means connecting the rearward ends of the two rods, and cushioning means interposed between 35 the frame and each connecting means at the ends of the rods, substantially as described.

2. In a device of the kind described, the combination of a frame, a shoe support 40 slidably mounted in the frame, and means slidably mounted in the frame and extensible with the shoe support adapted to provide an auxiliary support therefor, substantially as described.

3. In a device of the kind described, the 45 combination of a frame, a pair of rods slidably mounted in the frame, a shoe support connected to the forward ends of the two rods providing a stop, a connection between the two rods at their rear ends also providing a stop, and means for cushioning the engagement of the two stops with the frame, substantially as described.

JAMES G. HONTOS.
